UNITED STATES PATENT OFFICE.

GEORGE EDGAR HAZARD, OF ROCHESTER, NEW YORK, ASSIGNOR TO KELLOGG MANUFACTURING CO., OF ROCHESTER, NEW YORK.

AIR-PUMP.

1,221,504.

Specification of Letters Patent. Patented Jan. 14, 1919.

Application filed April 8, 1918. Serial No. 227,282.

To all whom it may concern:

Be it known that I, GEORGE E. HAZARD, a citizen of the United States, residing at Rochester, in the county of Monroe and State of New York, have invented certain new and useful Improvements in Air-Pumps, of which the following is a specification, reference being had therein to the accompanying drawing.

This invention relates to improvements in air pumps, and is particularly intended for two classes of service:—(a) for use in supplying air to large sized pneumatic tires on motor trucks, and (b) for garage use in supplying heavy air pressure to storage tanks for inflating automobile tires.

The invention is also adapted to be used wherever a small high duty air compressor is desired, and it may also be used for supplying air to an air-whistle on motor boats, and for supplying air pressure to air motor starting devices.

Where air pumps are used for inflating tires, it is necessary to prevent oil passing to the tires with the compressed air to avoid injury to the tires, and the primary object of my invention is to provide an improved oiling system so constructed and arranged that all of the movable parts of the pump are efficiently lubricated while at the same time compressed air is delivered free from any trace of oil.

Another object of the present invention is to construct the cylinder head with a chamber directly at the outlet side of the outlet valve to permit a free escape of the compressed air around and after it passes the valve.

Another object of the invention is to provide an improved spiral form of valve spring, whereby a very sensitive spring is provided; so that it can be compressed without the coils interfering with the action of the spring, and whereby a larger gage of spring wire can be used than with a straight spring; the larger wire is not so much affected by the heat of the pump as a smaller wire in a straight spring would be.

Another object of my present invention is to provide an improved manner of connecting the outlet manifold air-tight to the heads of the cylinders.

In the accompanying drawing—

Figure 1 is a vertical central sectional view of a pump embodying my improve-

ments, the compression end of one of the cylinders and the connecting end of its manifold being shown in side elevation.

Fig. 2 is an end elevation of my improved pump, partly in vertical section.

My improved pump is of the multiple cylinder type and as here shown comprises two cylinders 1, removably mounted side by side on a crank shaft case 2. The cylinders 1 are provided with flanges 3 through 6 which screw-bolts 4 pass into the crank shaft case 2, as shown, thus removably connecting the cylinders and the crank shaft case.

The type of pump here shown takes air through a suitable air-passage 5 into the crank shaft chamber 6, and this air passes into the open lower ends of the cylinders 1 and through an outlet opening 7, in each piston 8. The opening 7 is provided with a valve 9, the stem of which is guided and supported by a suitable valve guide 10, mounted in the head of the piston 8. A cone-shaped spiral spring 11 has its large end abutting against the guide 10, and its lower end held by a screw-nut 12 on the end 80 of the valve stem 13. The compressed air from the compression chamber 14 passes through a valved opening 15, formed in the head of the cylinder, and this opening is controlled by a valve 16. The stem 17 of 85 this valve is supported and guided by a suitable guide ring 18, and a conical spiral spring 19 has its large end abutting against this guide 18 and its small end engaging the head of the valve 16.

A suitable crank shaft 20 has its ends 21 journaled in end bearings 22, supported in the ends 23 of the crank case.

Pistons 7 are connected with the crank shaft by the connecting rods 24, which are provided with suitable bearings 25, while the opposite ends of the connecting rods are connected with the pistons by means of the usual wrist-pin 26. As here shown the wrist-pin 26 is locked in position in the piston by 100 a suitable screw 27.

As shown, the compression ends of the cylinders are connected by a manifold 28. My improved manner of connecting the manifold consists in providing a brass wedge-shaped packing 30, which is placed between the inner side of the screw threaded flange 31 of the cylinder head, and the end 32 of the manifold. This wedge-shaped packing 30 is forced to tight position by 110

means of the usual form of stuffing box nut 33, which engages the screw-threaded flange 31 and has a flange 34, which engages the thicker edge of the packing 30 and forces it tightly between the manifold and the flange 31. In this way, I am enabled to provide an absolutely air-tight connection between the manifold and the cylinder head.

Attention is directed to the construction 10 of the cylinder head 35, in that it is provided with a chamber 36 located outside of and surrounding the valve 16. This construction permits a free unimpeded passage of air from the compression chamber 14 around and beyond the valve 16 on its way to the manifold.

It will be observed that the cylinders are provided with vertically arranged cooling fins 37, which are found to be more efficient 20 than transversely arranged cooling fins, in that the air has a free upward passage past the fins, which is not the case when they are arranged transverse the cylinders and the cylinders supported in a vertical position. I find this arrangement of the cooling fins to be very efficient. However, this forms no part of my present invention and when desirable the cylinders may be water cooled by a suitable well-known water-jacket (not 30 shown).

A suitable hood 38 is located outside of the air-passage 5, and extends down a considerable distance, as shown in Fig. 2, and the air before it reaches the crank case chamber 6, 35 passes under the lower end of this hood or apron 38 and upward between it and the end of the crank case to the air passage 5. By this arrangement splashing mud and dirt is prevented from entering the pump with the 40 air that is passing therethrough.

Turning now to my improved oiling system, which is the primary improvement here disclosed, I provide an oil supply chamber or sump 40, which is below the crank shaft 45 chamber 6. Oil is supplied to this chamber 40, through a suitable oil filler 41, which has its opening provided with a detachable plug 42.

For the purpose of lubricating the pistons 50 and cylinders, I provide a felt oil pad 43, which is located between the adjacent lower ends of the cylinders. This felt pad is normally held upward by a suitable flat spring 44, and an oil supply wick 45 extends from 55 the pad 43 down into the oil chamber 40, as shown in Fig. 2. Oil is supplied by capillary action from the chamber 40, through the supply wick 45 to the pad 43, and this wick extends down both sides of the crank case 60 through channels 46 to the chamber 40. The felt spring 44 holds the pad 43 up so that it is touched by the lower end of the piston each time it moves down and is slightly depressed thereby. In this way the piston 65 takes up sufficient oil to furnish lubrication

between it and the cylinder wall and at the same time prevents any excess lubrication reaching the compression chamber 14 and being carried therefrom with the compressed air into the tire to be inflated.

The main bearings 21 are lubricated by lubricating wicks 47, which pass through channels 48, into the chamber 40, and the upper ends of the wicks are held in contact with the main openings by suitable spring rings 49, 75 which are located between the two-part main bearings 22. By this arrangement the wick is always held in contact with the main shaft and efficient lubrication of these bearings is insured.

The connecting rod bearings 25 are lubricated by a very slight amount of oil which is forced out of the pad 43 below the pistons when the pump is in operation. This oil collects at the bottom of the crank case and is just about enough to lubricate the bearings through a felt wick 50 carried by the connecting rod. Each time the connecting rod is in its lowest position, the wick 50 collects a little oil which is conveyed to the bearing with which it is in contact.

The cylinders, as here shown, are made singly, but they may be made in pairs, and also, as here shown, the cylinder heads 35 are made separate from the cylinders and screwed therein though it is not essential that the cylinder heads be made as a separate part.

As here shown, the pump is composed of two cylinders, but I desire it to be understood that my improvements are adapted to be used with a larger number of cylinders, and even with a single cylinder.

The bearings used in this pump are the Bound Book oilless bearing, or some similar type of bearing, so that if the placing of the oil in the pump should be neglected, it would operate for a considerable length of time without damage.

With an oiling system, as here shown, it is only necessary to pour oil through the filler 41 into the pump, and all bearings together with the piston and cylinders will be sufficiently lubricated, and the pump will deliver air free from any trace of oil for inflating tires.

A self lubricating bearing 51 is at the upper end of the connecting rod 24, and there is also provided a small opening 52 in the top of the said bearing through which any oil may pass to the bearing, should any collect in the under side of the piston or on the end of the valve stem.

As this pump is particularly intended for use under the car, where it is subject to mud, dust, water and all kinds of abuse of this nature, a suitable dust protecting felt 53 surrounds the exposed end of the crank shaft, and the hood 38 protects the air inlet opening 5.

An oil overflow 54 is provided for the crank-chamber to prevent accumulation of oil in the chamber, and this overflow extends to the outside of the pump, and is not in communication with the oil-supply chamber. This overflow positively prevents sufficient accumulation of oil in the crank-chamber to cause any splash.

10 A suitable number of screw-threaded holes 54' are formed in the case to receive bolts for attaching the pump under the car to a suitable bracket or other support (not shown).

Having thus described my invention, what I claim and desire to secure by Letters Patent is—

1. In an air pump, the combination with a cylinder having a valved air outlet opening in its head, a piston therein having a valved air inlet opening, a crank case in communication with the cylinder and having an air inlet, of an oiling system comprising an oil supply chamber at the bottom of the crank case, an oil pad located at the lower ends of the cylinders and a supply wick extending from the oil pad down to the oil supply chamber, whereby efficient lubrication is provided for the cylinder and piston and excess lubrication prevented, for the purpose described.

2. In an air pump, the combination with a cylinder having a valved air outlet in its head, a piston in the cylinder having a valved air inlet in its head, a crank case in communication with the cylinder and having a supply opening, of an oiling system comprising an oil supply chamber, an oil pad located at the lower ends of the cylinders, an oil supply wick extending from the pad to the oil supply chamber, and a spring holding the pad normally upward to insure engagement therewith of the piston, whereby efficient lubrication for the piston and cylinder is provided and excess lubrication is prevented, for the purpose described.

3. In an air pump, the combination with a plurality of adjacent cylinders each having valved air outlet openings in their heads and pistons for the cylinders each having valved air inlet openings, a crank case common to the cylinders and in communication with the lower ends thereof, the crank case having an air supply opening, of an oil system comprising an oil supply chamber, an oil pad located at the adjacent lower ends of the cylinders, and an oil supply wick extending from the pad to the oil supply chamber, whereby efficient lubrication for the cylinders and pistons is provided and excess lubrication prevented, for the purpose described.

4. In an air pump, the combination with a cylinder having a valved air outlet opening in its head, a piston having a valved inlet opening in its head, a crank case in communication with the piston, the crank case hav-

ing an air inlet opening, a crank shaft having bearings in the crank case and pivotally connected with the piston, of a lubricating system comprising an oil supply chamber below the crank shaft bearings, an oil pad 70 at the lower end of the cylinder, an oil supply wick extending from the pad to the oil supply chamber, and oil supply wicks extending from the oil supply chamber to each of the main bearings, whereby efficient lubrication is provided and excess lubrication is prevented, for the purpose described.

5. The combination with an air pump having a piston, a cylinder and a crank case, of an oil supply chamber at the lower portion 80 of the crank case, an oil pad at the lower end of the cylinder, an oil-supply wick extending from the pad to the oil supply chamber, and a spring holding the pad upward to insure engagement therewith by the piston for 85 lubricating purposes.

6. The combination with an air pump having a plurality of cylinders side by side, pistons therefor, a crank case common to the cylinders, an oil supply chamber below the 90 crank case, an oil pad at the center of the top of the crank case and at the lower ends of the cylinders, the crank case having a channel apart therefrom and communicating with the oil supply chamber, and an oil supply 95 wick extending from the pad through the said channel to the said oil supply chamber.

7. In an air pump, the combination of a plurality of cylinders side by side, pistons therefor, a crank case common to the cylinders, a crank shaft operatively connected with the pistons, the ends of the crank case having bearings for the said shaft, the crank case having an oil supply chamber below its bottom, the crank case having a channel extending therearound at its center, an oil pad at the top of the said channel, an oil supply wick extending from the top through the channel to the oil supply chamber, the case having end channels extending to the shaft 105 bearings, and oil supply wicks extending from the bearings through the channels to the oil supply chamber.

8. A crank case for air pumps, bearings in its ends for the crank shaft, and provided with an oil supply chamber below its bottom, the walls of the crank case having end channels extending to the said shaft bearings and with a channel extending around its center for the purpose of receiving oil 115 supply wicks for lubricating purposes.

9. In an air pump, the combination of a crank case, a cylinder mounted thereon, a piston within the cylinder, a crank shaft operatively connected with the piston, an oil 125 well below the crank shaft, a wick channel extending from the lower end of the cylinder to the said oil well, a wick passing through the channel to the oil well to provide lubrication at the lower end of the cyl- 130

inder, and a wick extending from the crank shaft into the oil well, the parts combined for the purpose described.

10. In an air pump, the combination of a 5 crank case, a cylinder mounted thereon, a lubricating pad at the lower end of the cylinder, a crank shaft journaled in the crank case, the crank case having an oil chamber below the crank shaft, and a wick channel 10 extending to the lubricating pad, a wick passing through the channel from the pad into the oil chamber, and a wick extending from the crank shaft into the oil chamber, whereby the piston and crank shaft are supplied with lubrication from the oil supply 15 chamber.

11. In an air pump, the combination of

a crank case, a cylinder mounted thereon, a piston within the cylinder, a crank shaft operatively connected with the piston, an oil receiving member at the lower end of the cylinder, an oil supply well outside of the crank case, a wick channel extending from the oil well to the oil receiving member, and a wick passing through the channel and 25 connecting the oil well with the oil receiving member for the purpose described.

In testimony whereof I hereunto affix my signature in the presence of two witnesses.

GEORGE EDGAR HAZARD.
